(57) **CLAIM**

The ornamental design for a drawer for refrigerator as shown and described.

DESCRIPTION

FIG. 1 is a front perspective view of a drawer for refrigerator showing our new design;

FIG. 2 is a back perspective view thereof;

FIG. 3 is a front view thereof;

FIG. 4 is a back view thereof;

FIG. 5 is a left side view thereof;

FIG. 6 is a right side view thereof;

FIG. 7 is a top plan view thereof;

FIG. 8 is a bottom plan view thereof;

FIG. 9 is a partial enlarged view of the area ‘9’ as identified in FIG. 1;

FIG. 10 is a back perspective view thereof, shown in an alternative configuration of use; and,

FIG. 11 is a front perspective view of the drawer for refrigerator, shown in an environment of use installed in a refrigerator.

The unevenly spaced broken lines in FIGS. 1 and 9 are for purposes of annotating the enlarged view only and form no part of the claimed design; the broken lines depict portions of the drawer for refrigerator that form no part of the claimed design. The portions of FIG. 11 drawn in broken lines show environmental structure only and form no part of the claimed design.
